UNITED STATES PATENT OFFICE.

HAROLD B. MORRIS, OF GLENDALE, CALIFORNIA.

METHOD OF MAKING MATERIALS FOR COVERING FURNITURE.

1,306,310.

Specification of Letters Patent. Patented June 10, 1919.

Continuation of application Serial No. 55,309, filed October 11, 1915. This application filed February 23, 1916. Serial No. 79,999.

To all whom it may concern:

Be it known that I, HAROLD B. MORRIS, a citizen of the United States, residing at Glendale, in the county of Los Angeles and 5 State of California, have invented certain new and useful Improvements in Methods of Making Materials for Covering Furniture, of which the following is a specification.

10 This invention relates particularly to the manufacture of material used in making chairs, settees and other articles of furniture but may also be used in the manufacture of other articles.

15 In my application for U. S. patent filed Oct. 11, 1915, Serial No. 55,309, I have shown some ways in which such material may be made, and my present invention involves certain improvements on the articles

20 and the methods shown, described and claimed in said application. I have found that very artistic effects may be obtained and very inexpensive and durable material produced by so making the core of the covering cord and so making and applying the

25 coverings thereto that not only are the coverings firmly united to the core but various color effects and designs may be given to the cord which may be preserved even when 30 the cord is partially worn away. The manner in which I do this and the various novel features of my invention will be hereinafter described.

In the accompanying drawings—

35 Figure 1 is a perspective view, illustrating how a covering cord embodying my improvements and consisting of a plurality of layers of material may be made.

Fig. 2 is a view on an enlarged scale and 40 in transverse section of the cord.

Fig. 3 illustrates one way of making the core.

Fig. 4 is a perspective view showing how the core may be covered.

45 Fig. 5 is a perspective view showing how the cord, after the final cover has been applied, may be twisted to cause it to resemble flag.

Fig. 6 shows how a braided covering may 50 be so applied as to leave open spaces whereby the next interior cover may be seen.

So far as part of my invention is concerned, the core may be made in various ways, such for instance, as that shown and 55 described in my application for patent filed

Oct. 11, 1915 above referred to and also in my application for patent No. 77,605, filed Feb. 11, 1916, and Patent No. 1,205,376, November 21, 1916.

The core A may be made of cotton waste, 60 raw cotton or similar material twisted into a cord and made compact. Preferably the core is made of masses of cotton waste or similar material differently colored. In Fig. 3, for instance, the part a of the core 65 may be red, the part a' green, and the part a'' blue. The masses of material may be dyed or colored before they are twisted and the masses of material may be twisted and drawn out or spun in the manner indicated 70 at a'' and otherwise treated until a compact core is produced. The core thus produced may be ornamented in any desired manner, as indicated in Fig. 1. After this, the core is treated with adhesive material b , which is 75 preferably flexible and which may contain waterproofing material. After the adhesive is applied it should be allowed to dry and then the adhesive should be heated by steam or otherwise to soften it. This may be done 80 in the manner described in my application of Oct. 11, 1915 above referred to.

While the adhesive is still soft the first cover B may be applied. This may be variously colored and it may be ornamented in 85 any desired way, as indicated. The designs on the cover may be made to match or register with the designs on the core. If it is desired to increase the size of the cord, adhesive material b' is applied to the cover B. 90 This may be of the same nature as that applied to the core. After the adhesive material is dried it is softened in the manner before described and another cover C may be applied. This cover may have any desired 95 color and it may carry any suitable designs, as indicated. These designs may match or register with the designs on the cover B so that if the outside cover is worn away in part the same designs carried by the inner 100 cover will appear. The coverings B and C may be applied in any suitable way and may be formed of any suitable material. They may be applied in the manner described and shown in my application of Oct. 11, 1915, or 105 in my Patent No. 1,205,376, November 21, 1916. After the cord is formed I preferably twist it in the manner indicated in Fig. 5, so that it will be made to resemble flag. After being thus twisted it should be 110

rolled or drawn through dies while in its twisted condition so that a permanent twist may be given to the cord.

As before stated the coverings B and C, and subsequent covers if they are used, may be applied in various ways. A very pleasing effect may be obtained by braiding the outer covering over the inner covering, as indicated in Fig. 6, and leaving open spaces whereby the inner covering may be exposed. In this way the outer covering may be given one color and the inner covering another color which will harmonize with each other. It is obvious that various designs may be produced in this way and that I have only illustrated a few of the many varieties that may be obtained.

It will be understood that the masses of cotton waste employed are colored before they are made into a strand or roving but that these masses are drawn out and twisted together in such manner that different colors will be exposed on the surface. In some parts of the roving the same color may appear all around it, while in other parts the same color may appear on different sides thereof.

When the covering B is applied it may be stained after it is applied so as to correspond with the exposed coloring of the core and similarly the covering C may be in like manner stained or colored after it has been applied, and the openings made in the covers B and C may be produced by suitable tools during the process of manufacture.

I claim as my invention:

1. The method herein described of forming a cord for covering frames of different articles which consists in forming the core of a plurality of different masses of differently colored fibrous material, such as cotton waste, twisting said material to form a compact core and to expose the different colors

in different places, treating the core thus formed with adhesive material, allowing the adhesive to dry into the core, then softening the adhesive and applying thereto a protective covering which is united to the core by the adhesive, coloring said covering to correspond in color effect with the inclosed adjacent portions of the core so that wearing away of said covering does not destroy the color scheme.

2. The method herein described of forming a flexible cord for covering frames of different articles, which consists in forming a core of a plurality of different masses of differently colored fibrous material, such as cotton waste, forming said material into a compact core, treating said core with adhesive material, allowing the adhesive to dry into the core, then softening the adhesive and applying thereto a protective covering which is united to the core by the softened adhesive.

3. The method herein described of forming a cord for covering frames of different articles, which consists in forming a core of a plurality of different masses of differently colored fibrous material, such as cotton waste, twisting said material to form a compact core and to expose the different colors in different parts of the core, treating said core with adhesive material, applying thereto a cover which is united to the core by the adhesive, coloring said cover to correspond in color effect with those portions of the core inclosed by the cover and in cutting away portions of said cover to expose the core.

In testimony whereof, I have hereunto subscribed my name.

HAROLD B. MORRIS.
